BLOCK-SIGNAL SYSTEM.

No. 851,456.

Specification of Letters Patent.

Patented April 23, 1907.

Application filed May 24, 1906. Serial No. 318,490.

To all whom it may concern:

Be it known that we, JULIAN VAN ZANDWEGHE, a citizen of the Kingdom of Belgium, and LUIS VIBERTI, a citizen of the Kingdom of Italy, and both residents of Rosario de Santa Fé, in Argentina, South America, have invented a new and Improved Block-Signal System, of which the following is a full, clear, and exact description.

10 Our invention relates to block signal systems, our more particular objects being to provide efficient means for stopping trains automatically when they approach each other within certain limits, and also for stopping them if desired when they approach a station.

Our invention further relates to certain mechanical details of construction, whereby the above objects are accomplished.

20 Reference is to be had to the accompanying drawings forming a part of this specification, in which similar characters of reference indicate corresponding parts in all the figures.

25 Figure 1 is a diagram showing two locomotives approaching each other and in position to stop automatically because of their proximity to each other; Fig. 2 is a diagram showing a locomotive as approaching a station and ready to cause an alarm at that station without causing the locomotive to stop; Fig. 3 is a fragmentary detail section of the trolley mechanism, carried by the locomotive for supplying current to the system from the wiring; Fig. 4 is an enlarged fragmentary section of the valve mechanism carried by each locomotive and operated electrically for the purpose of stopping the locomotive; and Fig. 5 is a diagram showing how the 40 wiring along the railroad track is divided into blocks insulated from each other.

The locomotives are shown at 6, 7 and are free to run upon the track 8. Each locomotive is provided with a pipe 9 connected directly with the boiler and conveying steam therethrough. Valve mechanism 10 is connected with this pipe 9, and from the valve mechanism extends a pipe 11 which by means of a flexible hose 12 is connected with the train pipe 13, the latter being connected with the air-brake so as to allow the brakes to release when the train pipe is vented. The valve mechanism 10 comprises a hand valve 14, whereby direct communication

may be established from the pipe 9 to the pipe 11. Another valve 15 is adapted to open and close communication between the pipe 9 and the pipe 11. The valve 15, however, is automatic in its action. It is provided with a stem 16 terminating in a stirrup 17, the stem 16 being encircled by a stuffing box 18 whereby it is rendered steamtight. A cam 19 is mounted upon a stub shaft 20 and is provided with an arm 21. This cam 19 engages the stirrup 17, and when in normal position as indicated in Fig. 4, maintains the valve 15 closed tightly upon its seat. Arms 22, 23 are mounted opposite each other as shown in Fig. 4, the arm 22 carrying a contact sleeve 22^a of metal. Extending through this sleeve is a spiral spring 24 insulated therefrom and connected with a contact member 25. A ring 26 of guncotton is connected by a link 26^a with the arm 21 and with a wire ring 26^b, connected with the arm 23. When the parts are in normal position, the ring 26 of guncotton holds the arm 21 in such position that the valve 15 is pressed tightly upon its seat as indicated in Fig. 4. Within the ring 26 of guncotton a detonator 27 of predetermined sensitiveness is embedded, for the purpose of exploding the guncotton ring. When the ring explodes it no longer retains the arm 21, and the latter being drawn by the spiral spring 24, turns a little and then allows the steam to open the valve 15 and pass through so as to operate the brakes.

Each locomotive 6, 7 is provided with a cab 28, upon the top of which is a bearing plate 29; see Fig. 3. Resting upon this bearing plate is a pedestal 30 secured in position by means of screwbolts 31 and 32. By removing these bolts the pedestal 30 may be turned around so as to occupy a reverse position upon the cab. This arrangement is desirable for the purpose of bringing the locomotives into shape for running in different directions. For instance, if a locomotive has finished its run, reaching one end of the line, and has started back on the return trip the pedestal 30 is turned around as above described. A bearing sleeve 33 engages the bearing plate 29 and also the pedestal 30, serving thus as a sort of pivot upon which the pedestal 30 may turn, the screwbolts 31, 32 having of course been removed. The trolley pole 34 is pivoted at 35 upon the pedestal 30, and is ten-

sioned by means of a spring 36. A trolley cord 37 is connected with the trolley pole 34 and passes downwardly through slots 30^a in the pedestal 30 and through the bearing 5 sleeve 33, and by pulling upon this trolley cord the trolley pole 34 may be lowered. The trolley pole is provided with a slot 38, and mounted within this slot are rollers 39 and 40 of conducting material. Pressing 10 upon these rollers respectively are contact leaf springs 41, 42, the two springs being connected with a wire 43. Insulators 44 and 45 are mounted upon arms 46, the latter being carried by posts 47. There are two rows of 15 these insulators as will be understood from Figs. 3 and 5. Wires 48, 49 are by means of insulating sections 50, 51 divided into distinct blocks which are staggered relatively to each other as indicated in Fig. 5. Each lo- 20 comotive carries a battery 52 and a switch 53 connected by a wire 53^a. Each locomotive also carries a ground wire 6^a; an electric bell 6^b, a pole changing switch 6^c and a hand switch 6^d, and a wire 7^e connecting the bell 25 6^b and the pole changing switch 6^c. From the latter a wire 54 connects with a wire 55, and connected with the wire 55 is a wire 56 from which a flexible wire connection 57 leads to the contact member 25 as shown in 30 Fig. 4, and a wire 58 is connected with the contact sleeve 22^a. From the wire 55 a wire 59 leads to the detonator 27, and through this detonator a wire 60 leads downwardly and is connected with the wire 58. A wire 35 61 is connected with the wires 58 and 60.

A station is shown at the right of Fig. 2, and from this station a wire 62 connects with the line wire 48. The line is supported upon insulators 48^a, 48^b. Mounted within the 40 station and connected with the wire 62 is a switch 63, from which lead wires 64, 65. Connected with the latter is a bell 66, and from this bell a wire 67 leads to the ground 68. A pole changing switch 69 is connected 45 by a wire 70 with a battery 71, and from the latter a wire 72 leads backward to the pole changing switch. The wire 67 is connected by a wire 73 with the pole changing switch.

Our invention is used as follows:—When a 50 locomotive is ready to travel in a predetermined direction, as for instance, when starting out from the end of the road, the trolley mechanism is arranged as shown in Fig. 3, the trolley pole 34 extending to the right or to the left, as the case may be, according to the direction in which the locomotive is to travel. The pole changing switch 6^c is also thrown into proper position, according to the direction of travel of the locomotive. For 55 locomotives traveling in one direction the pole changing switches 6^c should have the position indicated at the left of Figs. 1 and 2, whereas for traveling in the opposite direction they should have the position indicated 60 at the right of Fig. 1. Suppose, now, that

two locomotives, accompanied by their respective trains, are approaching each other. Sooner or later they reach such relative positions that they are not more than two blocks apart. In this event communication is established through either the line 48 or 49, as the case may be. Under no consideration can they come any nearer together than that represented by a distance of at least half a block. Arriving within this distance, the 70 following circuit is completed: ground wire 6^a of locomotive 6, (this wire being preferably grounded through the wheels) bell 6^b of that locomotive, wire 7^e, pole changing switch 6^c, switch 53 (now closed) wire 53^a, 75 battery 52, wire 61, wire 60, detonator 27, wire 59, wire 55, pole changing switch 6^c, wire 43 to line 48 (or 49 as the case may be), thence to the other locomotive, wire 43 of that locomotive, pole changing switch 6^c, 80 switch 53, battery 52, wire 61, wire 60, detonator 27 of locomotive 7, wire 59, wire 55, pole changing switch 6^c, wire 7^e, bell 6^b and ground wire 6^a, and thence through the earth 85 to its place of origin. The circuit thus completed causes each of the detonators 27 upon the respective locomotives to explode, and this explosion causes the destruction of the two rings 26 of guncotton. The springs 24 thereupon draw the contact members 25 into 90 engagement with the contact sleeves 22^a so as to shortcircuit the wires 59 and 60 which have hitherto been connected by means of the detonator 27. That is to say, the destruction of the detonator 27 does not leave 95 the circuit open, for the reason that a short-circuit consisting of the wires 56, 57, contact members 25, 22^a, and the wire 58 may take the place of that portion of the circuit represented by the detonator 27 and the wires 59 100 and 60. The contraction of the spring 24, and consequent movement of the arm 21 and the cam 19, opens the valve 15 and allows the steam to rush through to the brakes so as to stop the train as above described. Each locomotive is automatically stopped in this manner, and at the instant when the stoppage takes place the bell 6^b upon the locomotive rings violently.

Suppose, now, that the engineer wishes to 115 merely have his bell sound without having the locomotive stopped automatically. To accomplish this, he closes the switch 6^d. The switch 53 having of course been closed at the start, the following circuit is now completed whenever the two locomotives are within a predetermined distance limit of each other, to wit: ground wire 6^a, bell 6^b, wire 7^e, pole changing switch 6^c (right hand member) 120 switch 53, wire 53^a, battery 52, switch 6^d, pole changing switch 6^c (left hand member) 125 wire 43 of that locomotive, line 48 or 49 to the other locomotive 7, wire 43 of that locomotive, pole changing switch 6^c (left hand member) switch 53, wire 53^a, battery 52, 130

switch 6^d, pole changing switch 6^e (right hand member) wire 7^e, bell 6^b, to ground wire 6^a. This circuit enables the bells of the respective locomotives to be rung without interfering in any way with the action of the respective locomotives. Either or both of the locomotives can be prepared to this condition by merely closing or opening the switches 6^d. If it be desired to throw the signaling apparatus together, this is done by opening the switches 53. The bell 66 at the station (say righthand portion of Fig. 2) may be of greater sensitiveness than the bells 6^b upon the respective locomotives. When this is the case, the locomotive traveling toward the station will ring the bell at that station but will not be interfered with in the slightest degree. The pole changing switch 69 at the station is shifted into the one or the other of its two positions for the purpose of stopping the trains traveling in the one or the other of two directions. In the position indicated in Fig. 2, the pole changing switch 69 at the station is in proper position to stop the locomotive 6. In order to stop the locomotive the switch 63, however, should be shifted. The circuit through the locomotive has already been described. Through the station, however, the circuit is as follows: wire 39 48, wire 62, switch 63, pole changing switch 69, (right hand member), wire 72, battery 71, wire 70, pole changing switch 69 (left hand member) wire 73, and wire 67 to ground 68. This circuit stops the train as above described. If it be desired to merely give warning to the station agent as to the approach of the train toward the station, this is accomplished by placing the switch 63 in the position indicated at the right of Fig. 2. The 40 circuit from the line to the station is as follows:—line 48, wire 62, switch 63, wire 65, bell 66, ground wire 67 to ground 68. This

merely rings the bell at the station, and as above explained may either stop the train or not, depending upon the relative sensitiveness of the bell 66. 45

Having thus described our invention, we claim as new and desire to secure by Letters Patent:—

1. In a block signal system, the combination of a valve for controlling mechanism for stopping a train, means for holding said valve in a predetermined normal position, spring mechanism connected with said valve for releasing the same, a movable member connected with said spring mechanism, means for connecting to said spring mechanism a link of gun cotton for the purpose of temporarily holding said spring mechanism in a predetermined position, an electrically-operated detonator connected with said link of gun cotton for the purpose of exploding the latter, and electric mechanism controllable by movements of rolling stock for firing said detonator. 50 55 60 65

2. In a block signal system, the combination of a valve for controlling brake mechanism, a cam for holding said valve in a predetermined position, a spring for turning said cam, means for mounting a member of explosive material so as to hold said cam in another predetermined position, and electrically-operated mechanism controllable by movements of rolling stock for firing said member of explosive material. 70 75

In testimony whereof we have signed our names to this specification in the presence of two subscribing witnesses.
